UNITED STATES PATENT OFFICE

107,269

DESIGN FOR A MATTRESS

Charles T. Stirratt, Duluth, Minn.

Application April 19, 1937, Serial No. 68,857

Term of patent 14 years

To all whom it may concern:

Be it known that I, Charles T. Stirratt, a citizen of the United States and a resident of Duluth, in the county of St. Louis and State of Minnesota, have invented a new, original, and ornamental Design for Mattresses, of which the following is a specification, reference being had to the accompanying drawings, forming part thereof.

I claim:

The ornamental design for a mattress, as shown.

CHARLES T. STIRRATT,
